(57) **CLAIM**

The ornamental design for a surgical snare, as shown and described.

DESCRIPTION

FIG. 1 is a front perspective view of a surgical snare showing our new design;

FIG. 2 is a front view thereof, a rear view being a mirror image of FIG. 2;

FIG. 3 is a top view thereof, a bottom view being a mirror image of FIG. 3;

FIG. 4 is a right side view thereof;

FIG. 5 is a left side view thereof;

FIG. 6 is a front perspective view of another embodiment of a surgical snare showing our new design;

FIG. 7 is a front view thereof, a rear view being a mirror image of FIG. 7;

FIG. 8 is a top view thereof, a bottom view being a mirror image of FIG. 8;

FIG. 9 is a right side view thereof; and,

FIG. 10 is a left side view thereof.

The broken lines shown in FIGS. 1-10 illustrate portions of the surgical snare that form no part of the claimed design.

1 Claim, 6 Drawing Sheets
